UNITED STATES PATENT OFFICE.

WILBERT D. HENDERSON, OF SAN FRANCISCO, CALIFORNIA.

FURRING AND PARTITION CHANNEL.

1,227,264.

Specification of Letters Patent. Patented May 22, 1917.

Application filed April 21, 1915. Serial No. 22,971.

To all whom it may concern:

Be it known that I, WILBERT D. HENDERSON, a citizen of the Dominion of Canada, residing in the city and county of San Francisco and State of California, have invented a new and useful Improvement in Furring and Partition Channels, of which the following is a specification.

My invention relates to a furring and partition channel wherein opposed tongues having tapered ends are upset from the web of the channel and are arranged to rigidly embrace a second channel arranged transversely thereto; and the objects of my invention are first, to provide an improved channel adapted to rigidly embrace and secure a second channel arranged transversely thereto; second, to provide an improved channel of the character described whereby a cheaper and more rigid construction of furring and partitions may be obtained; and third, to provide an improved channel for furring and partition construction that is adapted to greatly facilitate the work of securing the various channels and members together.

I accomplish these several features by means of the device disclosed in the drawings forming a part of the present specification, wherein like characters of reference are used to designate similar parts throughout the said specification and drawings, and in which—

Figure 1 is a broken sectional view of a wall disclosing the channels secured thereto.

Fig. 2 is a side elevation of Fig. 1.

Fig. 3 is a plan view of Fig. 2.

Fig. 4 is a view similar to Fig. 1 but disclosing a modified form wherein the tapered ends are omitted.

Fig. 5 is a broken sectional view of the channel secured to a ceiling and supporting a transverse channel to which the metal ceiling lath may be secured.

Fig. 6 is a side elevation of Fig. 5.

Fig. 7 is a bottom view of Fig. 5 disclosing the manner in which the tapered ends of the tongues embrace the transverse channel.

Fig. 8 is a view similar to Fig. 5 but disclosing the tongues in a normal or open position for receiving the channel.

Fig. 9 is a view disclosing a modified form of the invention wherein only one of the tongue extends to the farther side of the embraced channels.

Referring to the drawings, the numeral

1 is used to designate a channel having opposed tongues 2 with tapered ends 3 thereon said tongues 2 being tapered in opposite directions and preferably formed integral with the web 4 of the channel 1 by being upset from the said web 4. The base of each tongue is formed with an arcuate portion 6 of such a radius as will not fracture the metal as would be the case were the said tongues bent sharply at right angles to the web 4.

The channels 1 are manufactured and delivered to the place of construction with the tongues 2 diverging as disclosed in Fig. 8 of the drawings, the angle of divergence being sufficient to separate the outer ends of the tapered portions or ends 3, a distance which will readily permit of the introduction or insertion of a second transverse channel.

After the second or transverse channel has been set between the tongues 2 the said tongues are bent so that the shanks thereof will lie parallel to each other and the outer or tapered ends 3 thereof will embrace and rigidly engage the farther side of the second or transverse channel, said tapered ends extending beyond each other in the same plane, as disclosed in Figs. 2 and 7 of the drawings.

In Fig. 4 I have disclosed a modified form wherein the tapered ends have been omitted as in this form a short channel is set horizontally in a wall or partition so that the end having the tongue 2 thereon will project slightly beyond the surface of the said wall or partition. In this form the transverse channel is supported mainly on the end of the channel 1, the tongues being utilized merely for the purpose of retaining the horizontal transverse channel 7 onto the channel 1.

The channel 7 is provided with tongues 2 having tapered ends 3 as hereinbefore described, said tongues 2 of the channel 7 embracing and rigidly engaging a vertically disposed transverse channel 8 to which the metal lath may be secured in the usual manner.

In Fig. 9 of the drawings I have disclosed another modified form of the channel wherein only one tongue is provided with an overlapping end 9, one overlapping end in this case, being sufficient to retain the second or transverse channel 7.

It is obvious that a partition constructed

of the hereinabove mentioned and described channels will possess stability, may be easily and cheaply constructed and will eliminate the cost and labor of the wire 5 fastening now in general use. It is also evident that a saving of time will be effected, such saving of time being an important factor in construction work of this character, by using the above described channels 10 for the reason that the tongues are formed at pre-determined regular intervals and it is only necessary to put the channels in place and by suitable pliers, or other adequate means, bend the tongues 2 and the 15 tapered ends 3 thereof into place so that the said tongues and tapered ends 3 thereof will rigidly embrace and engage the channels arranged transversely thereto.

Having thus described my invention, what 20 I claim as new and desire to secure by Letters Patent is—

Copies of this patent may be obtained for five cents each, by addressing the "Commissioner of Patents, Washington, D. C."

A furring and partition channel having opposed rectangular tongues with complementary tapered ends upset from the web thereof; a second channel arranged between 25 the tongues and transversely to the first mentioned channel, said tongues engaging the sides of the second channel and thereby rigidly retaining the same against the first mentioned channel, the rectangular portions of the tongues being arranged on two sides of the embraced channel and the complementary tapered ends projecting beyond each other in the same plane and on the 30 farther side of the second channel. 35

In witness whereof I hereunto set my signature in the presence of two subscribing witnesses.

WILBERT D. HENDERSON.
